United States Patent Office

Des. 188,446
Patented July 19, 1960

188,446

MAGNETIC PEN SUPPORT OR THE LIKE

Jacob M. Weiss, 5216 13th Ave., Brooklyn 19, N.Y.

Filed Mar. 10, 1958, Ser. No. 49,980

Term of patent 14 years

(Cl. D74—1)

Fig. 1.

Fig. 2.

Fig. 1 is a side elevational view of a magnetic pen support, showing my new design;

Fig. 2 is a front elevational view; and

Fig. 3 is a top plan view thereof.

The broken line showing of the pen is merely for purposes of illustration.

I claim:

The ornamental design for a magnetic pen support or the like, substantially as shown and described.
